[57] ABSTRACT

A stop detector for detecting a stop of a rotary device comprises a reed switch mounted on a fixed frame of the rotary device along the axis of its rotor and a pair of travelling magnets arranged so as to move perpendicularly to the axis of the rotor when centrifugal force is exerted. The travelling magnets move along a pair of non-magnetic guides fixed on the rotor and the non-magnetic guides are equipped with a pair of repulsive members at their far ends to give repulsive force to the travelling magnets when the rotor is halted thereby actuating the reed switch.

STOP DETECTOR FOR ROTARY DEVICE**BACKGROUND OF THE INVENTION****1. Field of the Invention**

The present invention relates to a novel stop detector for detecting a disconnection of a rotary device such as a cooling fan.

2. Description of the Prior Art

Cooling fans have been widely used in various fields of electrics and electronics for the purpose of preventing overheating, shortness of life, and change of characteristics. The operation period of a cooling fan is usually quite long and sometimes a cooling fan is required to operate continuously for several years. If a cooling fan fails, it is necessary that it be repaired or replaced as soon as possible. Accordingly, it has been proposed that a cooling fan be equipped with means for indicating a malfunction thereof.

The following types of detecting elements have been known.

- a. devices for detecting wind volume (for example a combination heater and thermal sensitive element)
- b. devices for detecting wind pressure
- c. devices for detecting the rate of revolution (for example a combination search coil and semiconductor logical circuit).

However, these devices have disadvantages and there is no satisfactory device having high reliability and low cost. For example, in the *a* devices, it is difficult to set the operation temperature since it is affected by atmospheric temperature. In the *a* and *b* devices, the effect of cooling fans of adjacent apparatus causes complications. The *c* devices have unusually complicated structures and are quite expensive.

SUMMARY OF THE INVENTION

It is therefore an object of the present invention to provide a novel stop detector for overcoming the above noted disadvantages.

The foregoing and other objects are attained in accordance with one aspect of the present invention through the provision of a stop detector for a rotary device which comprises a rotary member having a rotor comprising a non-magnetic central block having a center hole whose axis coincides with the axis of the rotor, the central block being fixed to the rotor of the rotary member, two non-magnetic guides bonded to the central block to extend symmetrically on an axis perpendicular to the axis of the center hole, a pair of travelling magnets freely fitted one on each non-magnetic guide so as to magnetically repulse each other, a pair of repulsing members mounted at each end of the non-magnetic guides, a stationary member comprising a reed switch, a supporter mounted to the frame of the rotary member, the reed switch being fixed to the supporter with one end of said reed switch mounted freely into the center hole of the central block.

BRIEF DESCRIPTION OF THE DRAWINGS

FIG. 1 is a plane view of one embodiment of a stop detector for a rotary member according to the invention;

FIG. 2 is a sectional view taken along the line A—A in FIG. 1;

FIG. 3 is a sectional view of a magnetic circuit used for a basic measurement;

FIG. 4 is a characteristic graph showing a balanced position by a repulsive force and a centrifugal force;

FIG. 5 is a plane view of another embodiment of the invention;

FIG. 6 is a sectional view taken along the line A—A in FIG. 1;

FIG. 7 is a sectional view of a magnetic circuit used for a basic measurement;

FIG. 8 is a characteristic graph showing a balanced position by a repulsive force and a centrifugal force;

FIG. 9 is a sectional view of another embodiment of the invention;

FIG. 10 is a schematic view of a reed switch used in the invention;

FIG. 11 is a performance characteristics curves of the stop detector for a rotary member according to the invention.

DETAILED DESCRIPTION OF THE PREFERRED EMBODIMENTS

One embodiment of the invention will be illustrated referring to FIGS. 1 and 2 wherein the reference numeral 1 designates a reed switch which is held by a supporter 7 mounted on a frame 8 for the rotary member and the end of the switch is freely inserted into a center hole 9 of the central block 2. The reed switch 1 is fixed to the supporter 7. The central block 2 is fixed to the rotor 6 and is made of non-magnetic material. The references 3, 3' represent non-magnetic cylinders fixed to the central block 2; 4, 4' represent cylindrical travelling magnets having an outer diameter which is slightly smaller than the inner diameter of the non-magnetic cylinder; 5, 5' designate repulsing members such as repulsing magnets fixed at ends of the non-magnetic cylinders and which have the same size as the cylindrical travelling magnets 4, 4'. The cylindrical travelling magnets 4, 4' and the repulsing magnets 5, 5' are magnetized in the axial direction. The directions of the magnetic poles are selected to be repulsive for 5 to 4; 4 to 4' and 4' to 5' as shown in FIG. 2.

When the rotor 6 formed by the rotating parts 2-5' is rotated, the centrifugal force acts upon the travelling magnets 4, 4' whereby the travelling magnets 4, 4' move against the repulsive force of the repulsing magnets 5, 5'. A desirable stop detector can be achieved by designating the magnetic circuit so that the travelling magnets 4, 4' turn on the switch 1 when the rotor stops and turn off the switch 1 when the rotor reaches its desired speed.

It should be emphasized that it is unnecessary to turn the switch 1 on or off depending upon the rotation of the cooling fan. In the case of a rate of revolution of 2,200 r.p.m., the life of the reed switch will be only one month because the life of a commercial reed switch is only about 100,000,000 ON-OFF times in the conventional structure which turns on by detecting the approach of the magnets fixed to the rotary member.

However, the life of the stop detector of the invention is quite long. In the specification, the rotary member, the stationary member and the reed switch are defined as follows. The rotary member comprises the central block 2; the travelling magnets 4, 4' and the repulsing members 5, 5' (magnets or springs) and the non-magnetic guides 3, 3'. The stationary member comprises the reed switch 1 and the supporter 7.

The reed switch comprises two magnetic flexible electrodes which are normally separated but which

contact each other when a magnetic field having a certain strength is applied. The electrode can have a free end which can be inserted into the center hole if desirable and the reed switch itself can be inserted into the central hole. In the central hole, the electrode can be magnetized by the travelling magnets as they approach the electrode causing the electrodes to contact each other to actuate the reed switch.

An experiment will now be described. FIG. 3 is a sectional view of a magnetic circuit for a basic measurement showing the operation of the invention. A glass tube having an inner diameter of 5.1 mm and a length of 42 mm was used as the non-magnetic cylinders 3, 3'. Four isotropical bariumferrite magnets having an outer diameter of 5 mm and a length of 5.9 mm which were magnetized as desired were inserted in the glass tube and the two magnets at the end were fixed to the glass tubes 3, 3' to be used as the repulsing magnets 5, 5'. In the normal state, the travelling magnets 4, 4', the two inner magnets, repulsed each other setting up a distance therebetween. The same distances were established for 5 to 4; 4 to 4' and 4' to 5'.

The glass tubes 3, 3' were bonded perpendicularly and symmetrically in the direction of the axis of rotation as shown in FIG. 2 to the surface of the rotor 6 of the cooling fan which had a rated revolution of 2,200 r.p.m. The cooling fan was rotated by applying a rated voltage and the inside of the glass tubes 3, 3' were observed using a stroboscopic method. It was found that the two travelling magnets 4, 4' were shifted to the far ends. When the rate of revolution was decreased by decreasing the applied voltage by variable voltage regulator (transformer), it was observed by decreasing synchronous frequency of the stroboscope that the travelling magnets 4, 4' approached each other with the decreasing rate of revolution as shown in FIG. 4.

Next, the turn-on and turn-off states of the reed switch (glass tube having an outer diameter of 3 mm and a length of 20 mm; about 30 AT) were observed by using the travelling magnets 4, 4' having the same size as abovementioned. The maximum distance between the positions of the magnets from the turn-off state to the turn-on state was 12 mm; and the minimum distance was 16 mm.

Finally, the stop detector shown in FIG. 2 was composed by using a reed switch, a glass tube having an inner diameter of 5.1 mm, the central block 2 and the supporter 7 made of bakelite (phenolformaldehyde resin). The relation between the turn-on and -off state of the reed switch and the rate of revolution was measured. In the experiment, the total length of the rotating member was 42 mm so as to coincide with the first experiment. The response of the reed switch was observed by changing the rate of revolution. The change from the turn-on state to the turn-off state occurred at about 920 r.p.m. and the change from the turn-off state to the turn-on state occurred at about 650 r.p.m.

The data are highly dependent upon the inserted depth of the reed switch 1 into the center hole 9 but are not substantially dependent upon the position of the stop detector (vertical and horizontal direction). As is clear from the experiment, it is possible to form a stop detector which works at a desirable rate of revolution of the rotor by combining the reed switch and the magnets in accordance with the invention.

In the experiment, in order to apply a force against the centrifugal force to the travelling magnets 4, 4', the

repulsing magnets 5, 5' were used as repulsive members. However, it is possible to replace the repulsing magnets by coil springs using the following calculation. The centrifugal force f_c is given by the equation:

$$f_c = m \left(r - \frac{l}{2} \right) \omega^2 \text{ [dyne]} \quad (1),$$

wherein m represents the mass [g] of the travelling magnets 4, 4'; r represents the distance of the two magnets from the central axis when they are balanced [cm]; ω represents the rate of revolution expressed in angular frequency and l represents the length of the travelling magnets 4, 4'.

The restoring force f_s of a coil spring is given by the equation.

$$f_s = 31 k (r - r_o) \text{ [dyne]} \quad (2),$$

wherein r_o represents the natural length of the coil spring [cm]; k represents a constant of the coil spring [dyne/cm].

The balanced position can be given by the equations 1 and 2;

$$r = \frac{l}{2} + \frac{\left(r_o - \frac{l}{2} \right)}{1 - \frac{m}{k} \omega^2} \text{ [cm]} \quad (3).$$

When the magnets are used as travelling magnets 4, 4' and the reed switch 1 is set so as to turn-off at 1000 r.p.m. wherein $r = 8 + 6 = 14$ [cm], the centrifugal force f_c is estimated as about 8000 dyne. If $r_o = 6$ mm, the constant k is about 9.050 [dyne/cm]. This means that a coil spring having a restoring force of about 1 g per 1 cm of contraction must be used. It is possible to provide such a coil spring by using a copper alloy wire having a diameter of 0.15 mm.

In the above-mentioned experiment or calculation, typical size magnets were utilized. However, it is possible to alter the size to use anisotropic ferrite magnets or Alnico magnets instead of isotropic ferrite magnets. The coil spring can be replaced by a conical spring or a spiral spring. This is a matter of design. Only the inner diameter of the non-magnetic cylinder is critical. Accordingly the outer surface is not limited to a circular sectional view but can be in the shape of a rectangle or a hexagon.

Another embodiment of the invention will be illustrated referring to FIGS. 5 and 6 wherein the reference numeral 1 designates a reed switch which is held by a supporter 7 mounted on a frame 8 for the rotary member. The end of the switch is freely inserted into a center hole 9 of the central block 2 and the switch 1 is fixed to the supporter 7. The central block 2 is fixed to the rotor 6 and is made of non-magnetic sliding shafts fixed to the central block 2; 12, 12', 12'' represent cylindrical travelling magnets having an inner diameter which is slightly larger than the outer diameter of the non-magnetic cylinder; 13, 13' designate repulsing members such as repulsing magnets fixed at the ends of the sliding shafts which are the same size as the cylindrical travelling magnets 12, 12'. The travelling magnets 12, 12' and the repulsing magnets 13, 13' are magnetized in the axial direction of the non-magnetic slid-

ing shafts 11, 11' and the directions of the magnetic poles are selected to be repulsive for 13 to 12; 12 to 12' and 12' to 13' as shown in FIG. 6.

When the rotating parts 12-13' are rotated, centrifugal force is applied to the travelling magnets 12, 12' causing the travelling magnets 12, 12' to move against the repulsive force of the repulsing magnets 13, 13'. A desirable stop detector can be obtained by designing the magnetic circuit so that the travelling magnets 12, 12' turn-on the switch 1 when rotation ceases and turn-off the switch 1 when the rated speed is achieved.

An experiment will now be described. FIG. 7 is a sectional view of a magnetic circuit for a basic measurement showing the operation of the invention. A brass rod having a diameter of 2 mm and a length of 42. mm was used as the non-magnetic sliding shafts 11, 11'. Four isotropical barium-ferrite magnets having an outer diameter of 5, 6 mm, an inner diameter of 2.5 mm and a length of 5.9 mm which were magnetized as desired were fitted to the rod. The two magnets at the ends were fixed to the far ends of the brass rods 11, 11' so as to function as repulsing magnets 13, 13'. In the normal state, the travelling magnets 12, 12', the two inner magnets, repulsed each other so as to establish a distance therebetween. Substantially the same distances were established for 13 to 12; 12 to 12' and 12' to 13'. The magnetic circuits were bonded perpendicularly and symmetrically in the direction of the axis of rotation as shown in FIG. 6 to the surface of the rotor 6 of the cooling fan which rotates at a rated revolution of 2,200 r.p.m. The cooling fan was rotated by applying a rated voltage and the position of the travelling magnets 12, 12' was observed using a stroboscopic method whereby it was found that two travelling magnets 12, 12' were shifted to the far ends.

When the rate of revolution was decreased by decreasing the applied voltage through the use of a variable voltage regulator, it was observed by decreasing the synchronous frequency of the stroboscope that the travelling magnets 4, 4' approached each other as the rate of revolution decreased as shown in FIG. 8.

Next, the turn-on and turn-off states of the reed switch (glass tub having an outer diameter of 3 mm and a length of 20 mm; about 30 AT) were observed by using travelling magnets 12, 12' having the same size as above-mentioned. The maximum distance between the positions of the magnets from the turn-off state to the turn-on state was 11.5 mm; and the minimum distance was 15.5 mm.

The stop detector shown in FIG. 6 was composed by using a reed switch, a brass rod having a diameter of 2 mm, the central block 2 and the supporter 7 made of a bakelite (phenol-formaldehyde resin). The relation between the turn-on and turn-off state of the reed switch and the rate of revolution was measured. In the experiment, the total length of the rotor was 42 mm so as to coincide with the first experiment. The response of the reed switch was measured by changing the rate of revolution. The change from the turn-on state to the turn-off state occurred at about 900 r.p.m. and the change from the turn-off state to the turn-on state was at about 620 r.p.m. The data were highly dependent upon the inserted depth of the reed switch 1 into the center hole 9, but the data were not substantially dependent upon the position of the stop detector. (vertical and horizontal direction).

An embodiment of the stop detector wherein the reed switch and the magnets are combined has been proposed. The stop detector responds when the rotary member reaches a certain rate of revolution which is lower than a desired rate of revolution. However, in the stop detector, the reed switch which is freely inserted into the center hole of the central block is comprised of a brittle glass tube. The accuracy of the clearance for a free fit is therefore quite important. If the reed switch is assembled with too large a clearance the glass tube may be broken.

Another embodiment of the invention which is suitable from the above-mentioned standpoint will now be described with reference to FIGS. 9 to 11. In FIG. 9, the reference numeral 2 designates a central block having a center hole 9 which is made of non-magnetic material; 3, 3' designate non-magnetic guides such as brass tubes which are mounted symmetrically to the central block 2 and vertically to the center hole 9; 4, 4' designate travelling magnets which may be, for example, of cylindrical shape and which are respectively freely fitted to the non-magnetic guides 3, 3'; 5, 5' designate repulsing members such as repulsing magnets which are respectively fixed at each end of the non-magnetic guides 3, 3'.

The rotary member of the stop detector comprises parts 1-5' and is fixed to the rotor 6. Its center coincides with the rotary shaft 10a of the rotor 6 and the central axis of the center hole 9. The reference numeral 7 is a supporter mounted to the frame 8 for the rotor 6 and 1 designates a reed switch. The lower end of the switch is inserted into the center hole 9 and the upper end of the switch is fixed to the supporter 7. The supporter 7 and the frame 8 form the fixed part of the stop detector. The travelling magnets 4, 4' and the repulsing magnets 5, 5' are magnetized in the axial direction and the directions of the magnetic poles are selected to be repulsive for 5 to 4; 4 to 4' and 4' to 5. In the rest state, the travelling magnets 4, 4' are disposed at a balanced position with respect to the central block.

When the rotor 6 is rotated, centrifugal force is applied to the travelling magnets 4, 4' causing the travelling magnets 4, 4' to move against the repulsive force generated by the magnets 5, 5'. The reed switch 1 detects the movement of the travelling magnets 4, 4' and turns on when the rotor 6 ceases rotation and turns off when the rated speed is attained. Thus, the magnetic circuit is dependent upon the balance of the centrifugal force and the repulsive force.

The minimum distance and the maximum distance between the travelling magnets 4, 4' are set depending upon the response (ampere turns) of the reed switch 1. The response depends upon the selection of the reed switch 1 and also the depth of insertion into the center hole 9. Accordingly, data is secured by experimentation.

In the embodiment shown in FIG. 10 the reed switch 1 has an asymmetrical shape. The reed switch 1 has a long electrode 14 and a short electrode 15 sealed in a glass tube. In the asymmetrical switch 1, it is possible to turn-on the switch by causing the travelling magnets 4, 4' to approach the magnetic wire 16 of the short electrode as shown in FIG. 10. Accordingly, in the embodiment shown in FIG. 10, the part of the reed switch which is inserted into the center hole 9 is not the glass tube but is the magnetic wire 16 of the short electrode 15.

From the view point of the magnetic circuit, if there is equivalence whether the travelling magnets 4, 4' are at the positions of the full line or the dotted line in FIG. 10, it is to be understood that the reed switch 1 can be utilized as stated above. The advantages of the use of the reed switch 1 are as follows:

1. It is unnecessary to accurately adjust the clearance of the center hole 9 and the reed switch 1.
2. The tolerances for the parts are rather large so that the cost of the parts and the assembly thereof can be decreased.
3. There is no difficulty even though the free fit is altered by long operation. Accordingly, the reliability of the device is improved.
4. The travelling magnets 4, 4' can approach closer to the reed switch 1 so that the magnetic gap is small. Accordingly, the size of the travelling magnets 4, 4' can be made small and the total size can be compacted.
5. The wiring from the magnetic leading wire 16 is a relatively simple matter.

One experiment with respect to this embodiment will now be described. A brass tube having an outer diameter of 5.5 mm, an inner diameter of 3.5 mm and a length of 35 mm was prepared and a center hole 1a having a diameter of 3 mm was formed in the tube. An opening having a diameter of 4.2 mm was drilled to a depth of 15 mm from the ends of the brass tube in the center of the step shape. In the experiment, the central block 2 and the non-magnetic guides 3, 3' were formed in one piece.

Four isotropic barium ferrite magnets having a diameter of 4 mm and a length of 5 mm were magnetized as desired and were inserted into the brass tube to form the rotary part of the stop detector. The stop detector was prepared by using a commercial reed switch 1 (glass tube having a diameter of 2 mm and a length of 9 mm; response AT of 20-35; off-set type), a supporter 7 made of bakelite (phenolformaldehyde resin) and a cooling fan having a rated revolution of 2,200 r.p.m.

The vertical position of the reed switch 1 was made moveable and a measurement was made for the relation between the depth of insertion of the magnetic wire 16 into the center hole 9 and the the rotating revolutions per minute for the stop detector.

FIG. 11 shows the results of measurements. The pharmetry designates the total length of the magnetic wire 16 and the short electrode 15. As shown in FIG. 11, is not necessary that x, y, be extremely accurate because the detector can satisfactorily respond at speeds of 600-900 r.p.m. As it is clear from the above statements, the stop detector of the invention has a remarkably high reliability and a rather low cost.

Thus, the industrial value of the invention is remarkably high.

Obviously, numerous modifications and variations of the present invention are possible in light of the above teachings. It is therefore to be understood that within the scope of the appended claims the invention may be practiced otherwise than as specifically described herein.

What is claimed as new and desired to be secured by letters patent of the United States is:

1. A stop detector for a rotary device which comprises:

a rotary member having a rotor comprising:
a non-magnetic central block having a center hole whose axis coincides with the axis of the rotor;
the central block being fixed to the rotor of the rotary member;
two non-magnetic guides bonded to the central block to extend symmetrically on an axis perpendicular to the axis of the center hole;
a pair of travelling magnets freely fitted one on each non-magnetic guide so as to magnetically repulse each other;
a pair of repulsing members mounted at each end of the non-magnetic guides;
a stationary member comprising a reed switch;
a supporter mounted to the frame of the rotary member;
the reed switch being fixed to the supporter with one end of said reed switch mounted freely into the center hole of the central block.

2. The stop detector according to claim 1 wherein the non-magnetic guides comprise cylindrical tubes and the travelling magnets are cylindrical.

3. The stop detector according to claim 1 wherein the non-magnetic guides comprise guide shafts and the travelling magnets each have a guide hole.

4. The stop detector according to claim 1 wherein the reed switch comprises a first electrode and a second electrode sealed in a tube, one end of the second electrode being disposed without the tube, said one end of the second electrode being freely mounted in the center hole.

5. The stop detector according to claim 1 wherein the repulsing members comprise coil springs.

6. The stop detector according to claim 5 wherein the coil springs comprise copper based alloys.

7. The stop detector according to claim 3 wherein the non-magnetic guide shafts comprise cylindrical rods and the travelling magnets comprise cylindrical tubes.

8. The stop detector according to claim 1 wherein the non-magnetic guides and the central block comprise one piece.
